UNITED STATES PATENT OFFICE.

MELBERN BERNIE BULLA, OF EL PASO, TEXAS.

METHOD AND MEANS FOR REMOVING CAR BRASSES.

Application filed March 1, 1927. Serial No. 171,902.

In the process of removing brasses from car journals, it is customary to place a jack under the journal box and lift the box free of the axle to an extent sufficient to allow the brass to be pulled up over the collar on the end of the axle and to be removed from the box. In this operation, the weight of the car is thrown more upon the other end of the axle, thereby tending to lift the wheel 10 near which the brass is to be removed. This would consequently raise the axle with the bearing so that the axle does not readily separate from the bearing to permit the removal of the latter.

15 The object of my invention is to provide means and a method for overcoming this difficulty. The invention comprises a clamping device adapted to be applied so as to hold the wheel to the rail, and to this end 20 it has upper and lower jaws for fitting respectively over the outer rim of the wheel and under the head or top of the rail. It further comprises an adjustable feature whereby such clamping device can be made 25 to accommodate wheels and rails having various thicknesses of rims and heads respectively. It further comprises a method of applying such clamps so that they will be held in place by the jack itself, to prevent 30 them from slipping off the inclined faces of the wheel rim and rail head. It further provides means attachable to the clamps for thus utilizing the jack as an abutment to hold the clamps tight against the rim and 35 rail.

In the accompanying drawing:

Figure 1 is a side elevation of a car wheel and axle with the rail and part of the wheel shown in section.

40 Figure 2 is a transverse section through the journal box.

Figure 3 is a view on an enlarged scale of one form of clamp.

45 Figure 4 is a view of another form of clamp.

In Figure 1, 1 indicates a cross tie, 2 a railway rail, 3 a railway car wheel, 4 the axle for the same, and 5 a journal box. At 50 6 is shown a jack adapted to rest on the tie 1 and be brought to bear under the bottom of the journal box 5. To hold the wheel 3 down when the jack is applied, I provide a clamp 9 having two jaws, one adapted to fit over the inner periphery of the wheel rim 55 and the other adapted to fit under the head

of the rail. As both the rims of the wheel and the rail heads may vary in thickness, I would in that case make the clamp adjustable. In Figure 3 is shown a clamp made of two members, one member 10 having recesses 11 and the other member 12 having protuberances 13 adapted to fit in the recesses of the first-mentioned clamp. A thumb screw 14 or bolt, or other means such as a clamping ring 15, may be used to 60 hold the two parts of the clamp together. It will be seen that by loosening the screw, one member may be slid along the other until the protuberances 13 match the proper holes 11 to make the distances between the 65 ends of the clamps fit the particular rail and wheel to which they are to be applied. In Figure 4, the same object is accomplished by means of a hollow clamp member 16 made of malleable iron or cast steel, with a matching member 17 adapted to pass through the same and be held in its proper position by means of a key passed through slots 18 in the two members, one or both members having a plurality of slots to provide for the 70 requisite adjustment. At the back of the clamp, I prefer to attach a brace 19 of proper dimensions to occupy the space between the jack and the clamp, to hold the clamp firmly 75 up against the inclined faces of the wheel rim and rail head. With this precaution, the clamp is not liable, when the strain is applied, to slide off these inclined faces.

While I have shown a particular embodiment of my invention, it will be understood 80 that in its general features the invention will cover many other forms.

I claim:

1. A clamp for clamping a car wheel to the rail when the car is lifted by a jack, said 90 clamp having curved jaws for engaging the wheel rim and the underside of the rail head and a curved brace permitting the clamp to rest in engaging position against the lifting jack irrespective of the contour of the latter. 100

2. A clamp for clamping a car wheel to the rail when the car is lifted by a jack, said clamp having curved adjustable jaws for engaging the wheel rim and the underside of the rail head and a curved brace 105 permitting the clamp to rest in engaging position against the lifting jack irrespective of the contour of the latter.

MELBERN BERNIE BULLA.
